UNITED STATES PATENT OFFICE.

THEODORE A. TAYLOR AND ANTON J. YEAGER, OF WISCONSIN RAPIDS, WISCONSIN,
ASSIGNORS TO PRENTISS-WABERS STOVE COMPANY, OF WISCONSIN RAPIDS, WIS-CONSIN, A CORPORATION OF WISCONSIN.

DESIGN FOR A STOVE.

Application filed December 27, 1921. Serial No. 525,254. Term of patent 3½ years.

To all whom it may concern:

Be it known that we, THEODORE A. TAYLOR and ANTON J. YEAGER, citizens of the United States, residing at Wisconsin Rapids, in the county of Wood and State of Wisconsin, have invented a new, original, and ornamental Design for Stoves, of which the following is a specification, reference being had to the accompanying drawing, forming part thereof.

The drawing shows a stove embodying this invention in perspective.

We claim:—

The ornamental design for a stove, as shown.

THEODORE A. TAYLOR.
ANTON J. YEAGER.
